UNITED STATES PATENT OFFICE.

SAMUEL J. WARNOCK, OF CHICAGO, ILLINOIS, AND JOSEPH J. NEUMAN, OF BEAVER DAM, WISCONSIN.

RADIATOR-BUSHING.

1,097,780.

Specification of Letters Patent. Patented May 26, 1914.

Application filed June 16, 1911. Serial No. 633,465.

To all whom it may concern:

Be it known that we, SAMUEL J. WARNOCK and JOSEPH J. NEUMAN, citizens of the United States, residing at Chicago, in the county of Cook and State of Illinois, and at Beaver Dam, in the county of Dodge and State of Wisconsin, respectively, have invented certain new and useful Improvements in Radiator-Bushings, of which the following is a specification, reference being had to the accompanying drawing, forming a part thereof.

This invention relates more particularly to the supply and return connections for hot water radiators.

Its main objects are to facilitate making such connections; to admit of the use of standard fittings, unions, valves and elbows for the supply and return connections; to make both connections with the radiator close together near the floor, thus avoiding cumbersome, inconvenient and unsightly connections with the upper part or with different parts of a radiator; to admit of removing and replacing defective parts of either connection, valve, union or elbow without loss of other parts; and generally to improve the construction and operation of devices of this class.

It consists in the construction, arrangement and combination of parts as herein-after particularly described and defined in the appended claim.

In the accompanying drawing like characters designate the same parts in the several figures.

Figure 1 is an outer end elevation of the bushing in connection with the lower part of a radiator section and supply and return connections as they are assembled in practice; Fig. 2 is a horizontal section on the line 2 2, Fig. 1; Fig. 3 is a side elevation of the bushing; and Fig. 4 is an inner end elevation thereof.

The bushing constituting the principal feature of the invention, consists of an externally threaded collar *a*, which is fitted into the standard threaded opening in the lower part of one of the end sections *b* of a radiator. It is formed at the outer end with a squared or polygonal wrench head *c*, to facilitate its insertion in and removal from the radiator section, and has two horizontally diverging internally threaded branches

d and *e* for the standard supply and return connections of the radiator.

Hot water radiator sections are usually made with openings of the same standard size in opposite sides of the lower parts thereof, for connecting the sections in the usual manner with nipples, and one of these openings in the outer side of one of the end sections serves for making the supply and return connections by means of the bushing which constitutes the principal feature of the present invention. These bushings are therefore made with collars of the same size and threaded to fit the standard opening in any radiator section. The converging ends of the coupling nipples point directly into the threaded part of the collar, their threaded parts lying within the area of the wrench head thereof. They are also made with branches of different sizes for standard pipe and fittings used with hot water radiators for making the supply and return connections.

A partition, *f*, preferably arranged horizontally, divides the collar into upper and lower passages, and at the outer end is so twisted that the upper passage communicates with an inlet pipe, *g*, and the lower passage communicates with an outlet, *h*, the inlet and outlet being both in the same horizontal plane. At its inner end the partition *f* is curved or bent upwardly so as to deflect and direct the inflowing hot current of water upwardly into the upper part of the radiator and thus separate it from and prevent its interfering with the outflowing current of cold water which is deflected and directed thereby into the outlet passage *h*. The free and effective circulation of water through the radiator is thus promoted.

Coupling nipples *i* are threaded in the branches *d* and *e*, and a standard valve *j* for controlling the supply of hot water to the radiator is detachably connected with the nipple of the supply branch *d* by a coupling collar *k*, while a standard elbow *l* is detachably connected with the other nipple in like manner, by a collar *k*. The supply and return pipes *m* and *n* are threaded respectively in the case of valve *j* and in the elbow *l*, leading downwardly therefrom parallel with each other and close to the radiator through the floor near which the supply and return connections with the radiator are made.

The branches *d* and *e* of the bushing point obliquely out from the collar, and at such an angle to each other that the supply and return pipes *m* and *n* are separated sufficiently to allow for the usual floor plates *o* being placed around the pipes to cover the openings therefor in the floor without interference, as shown in Figs. 1 and 2.

A small opening *p*, as shown in Fig. 4, is made through the wall of the bushing between the inner and larger end of the inlet passage *g* and the outer and smaller end of the outlet passage *h*, to prevent the radiator from becoming air bound.

By the employment of a bushing constructed as herein shown and described, the standard fittings, valves, elbows, couplings and pipes employed in the ordinary manner with hot water radiators may be used in making the supply and return connections through the same opening at one end of a radiator, and in case a valve or any other part of these fittings is defective, it can be removed and replaced without loss of other parts, as in that class of fittings in which the valve or valve case is formed integrally with the return connection, thereby avoiding inconvenience not only in installing but also in repairing the connections of hot water radiators, besides effecting a saving in expense.

It will be seen that the device of our invention, embodies in a single integral structure, a radiator bushing having independent supply and return passages together with branches so disposed that the usual fittings of the valve supply pipe and the return pipe, can be employed. Furthermore, by reason of the horizontal disposition of the axes of the branches and the bore of the bushing, we are able to provide a bushing which presents a symmetrical and neat appearance such as is necessary in an attachment of this character. The accomplishment of this object is partly due to the fact that the axes of the two branches and of the bore are horizontally disposed and division of the supply and return water is effected in the bore of the bushing by the horizontal partition and in the branches, by the vertically disposed partitions, one of which serves to close one branch to one passage, and the other of which serves to close the other branch to the remaining passage. Combined with all these advantages we provide a bushing which does not extend inwardly into the interior of the radiator section, and which has a partition which does extend into the interior of the radiator section substantially completely across the zone of ingress and

egress to and from the bushing so as to most effectively divide the supply and return flows. By reason of the fact that the axes of the bore and the branches are horizontally disposed, and also by reason of the fact that we provide horizontal and vertical partitions, we are able to provide a discharge for the supply branch which exceeds the cross section of the supply branch itself, and likewise, we are able to provide an intake area or passage for the return branch which exceeds in cross section, the cross section of the return branch. Thus no choking or retarding of the flow is possible either from the supply branch or to the return branch.

Various changes in details of construction of the device may be made without materially affecting its operation or departing from the principle of the invention.

We claim:

In combination, a hollow radiator section having a threaded opening, a bushing having a main bore and a threaded portion adapted to be turned into but not extending appreciably inwardly beyond the inner end of the threaded opening, said bushing having substantially horizontally disposed supply and return branches diverging substantially horizontally from the longitudinal axis of the bushing bore and a substantially horizontal partition dividing said bore into upper and lower passages for a portion of the length of said bore and projecting beyond the bushing into the hollow radiator section substantially completely across said hollow radiator section, said bushing having upper and lower vertically disposed partitions extending substantially longitudinally of said bore for a portion of their length and diverging in opposite directions substantially transversely of the longitudinal axis of the bore to close the return branch to the upper passage formed by said horizontal partition and to close the supply branch to the lower passage formed by said horizontal partition, the cross section of each passage exceeding the cross section of the respective branch with which it communicates and the axes of the branches and said bushing being horizontally disposed.

In testimony whereof we hereto affix our signatures in presence of two witnesses.
